UNITED STATES PATENT OFFICE.

GEORGE FISHER, OF CLEVELAND, OHIO.

REFILLABLE FUSE-TUBE.

1,086,909.

Specification of Letters Patent.

Patented Feb. 10, 1914.

Application filed February 10, 1913. Serial No. 747,258.

To all whom it may concern:

Be it known that I, GEORGE FISHER, of Cleveland, in the county of Cuyahoga and State of Ohio, have invented new and useful 5 Improvements in Refillable Fuse-Tubes, of which the following is a specification.

This invention relates to fuses for electric circuits, and to means for safely connecting and inclosing them.

10 The objects of my present invention are, to provide convenient and readily accessible means for inclosing a fuse to eliminate fire danger; to provide a casing and connections adapted to receive a new fuse without delay 15 upon the burning out of the fusible connection; to provide a self-contained fuse attachment instantly separable from its casing, but contacting automatically upon the closing of the casing; and to produce an efficient and 20 more readily refillable inclosed fuse tube, and at less expense for manufacture, than the devices for the purpose now in general use.

Further advantages of the invention will 25 become apparent to those familiar with the art upon perusal of the following description.

Referring now to the accompanying drawings illustrating preferable embodiments of 30 my invention:—Figure 1 is a plan view, and Fig. 2 is an end elevation of a fuse tube connected up in an electric circuit. Fig. 3 is a longitudinal section of the tubular casing and fuse gripper bar. Fig. 4 is another 35 lengthwise section of the casing, with the fuse gripper arrangement shown in plan view. Fig. 5 is an end elevation of a modified form of end cap, and bracket connection. Fig. 6 is a detailed side elevation of one end 40 of the fuse gripper and bar.

The reference letter *a* indicates the outer casing for the device, preferably of hard fibrous, or other suitable electrically insulating material, which, for purposes of strength 45 and convenience of manufacture, should be tubular in form. The interior of the casing *a* should be lined throughout with insulating and non-combustible material, as shown at *b*, closely fitted, or adhering, to the casing. A 50 metallic cap *e* is flanged to fit closely over one end of the casing *a*, and is fixedly secured thereto in any suitable way, as by means of the depressions *d* punched in the flange of the cap so as to engage corresponding 55 depressions in the casing *a*. A similar metal cap *c* is fitted to slide over the other end of

the tube *a*, so as to be readily removable; and one or more spring latches *f* are secured to its cylindrical flange, each latch being provided with suitable means of engagement with the tube, such as a hole *g* in the latch adapted to spring over a pin *h* firmly fixed to and projecting from the tube *a*. Thus by raising the latch *f*, the cap *e* may be slipped off of the tube *a*; but when the cap is replaced and pressed against the end of the tube, the latch *f* springs into place and retains the cap securely on the tube.

The removable fuse holder comprises a bar *j* of hard vulcanized fiber, or other suitable electrically insulating material, carrying upon each of its extremities a metallic spring clamp *l*, adapted to receive and hold a wire, or strip *k* of metal fusible at a relatively low temperature. The fuse holder 75 bar *j* is preferably of a rectangular cross-section, and should be wrapped or inclosed in a covering *i* of insulating and non-combustible material. The fuse holders *l* are 80 of spring metal, substantially duplicates of each other, and firmly secured respectively to the ends of the bar *j* by rivets *r*, as shown, or in any suitable way. Each holder clamp may be made of two strips of metal, but I 85 prefer to use a single flat strip doubled upon itself, as shown, and secured to the side of the bar *j*. The ends of the spring clamps are initially bent to a slightly obtuse angle with, and overhang the ends of, the bar *j*, as shown in Fig. 6. A groove, or socket, is 90 formed in the inner side of one of the overhanging ends of the clamp to receive the fuse wire *k*, and this socket is preferably an outward crimp *m* of the longer end, as shown, disposed approximately in line with the central axis of the bar *j*. A small bend *n*, opposed to said socket, may be made in the shorter, or opposite, end of the spring clamp, and both ends of the clamp may be 95 slightly flared to facilitate the introduction 100 of the fuse wire.

It should now be readily understood that to load the device, the ends of a fuse wire *k* are sprung between, and gripped respectively by, the ends of the spring clamps *l*, the fuse wire being carried from end to end alongside the bar *j*, and the latter inserted in the tube *a*. In pressing the metal cap *e* into place upon the casing, the fuse clamps *l* are intercepted between the casing caps *c* and *e*, said caps pressing respectively upon the salient bends *m* and further bending the 110

ends of the clamps *l*, thereby gripping the fuse wire more tightly in said clamps, and at the same time making excellent electric contacts between said clamps and caps.

5. The tube is connected in circuit in the usual, or any suitable way, but I prefer to form upon each of the metal caps *c* and *e* a flat wing, or fin, *p* projecting endwise therefrom, which may be readily slipped between forked, or otherwise oppositely disposed, spring contact brackets *q*, connected in circuit, and secured to a support, as shown in Figs. 1 and 2. If the spring contacting brackets are formed as at *s* in Fig.

- 10 5, the blades *p* may be dispensed with, and the tubular portions of the caps *c* and *e* gripped between the forks of the brackets.

Thus, the fuse may be readily replaced or inspected, and all the members of the device used continuously; nothing being discarded upon the blowing of a fuse, except the short length of fuse wire *k*. Small apertures, as at *o*, may be made in the tube *a* and its lining to ventilate the tube; and 20 to serve as vents upon the burning out of a fuse; but these apertures should not be large enough to release hazardous jets of flame.

It is obvious that the casing *a* may be 30 filled about the fuse and its holder with the usual non-combustible powder, if desired, but this will seldom be advantageous.

I further point out and distinctly claim as my invention—

- 35 1. In an electric fuse, a shell having a removable cap, a removable insulation bar therein, metallic clamps secured approximately at and overhanging the respective ends of said bar, and a fusible wire gripped 40 by and connecting said clamps.

2. In an electric fuse, a shell, a cap closing and fixedly secured to one end of said shell, a cap removably attached to the other end of said shell, and an unattached fuse

- 45 holder bar provided with elastic means for making contact with said caps.

3. In an electric fuse, a shell, a cap fixedly secured to one end of said shell, a cap removably attached to the other end of said

shell, an unattached fuse holder bar, and 50 spring clamps at the ends of said bar adapted to receive and hold a fuse thereto and when inclosed in said shell to contact respectively with said caps.

4. In an electric fuse, a shell, a cap fixedly secured to one end of said shell, a cap removably attached to the other end of said shell, an unattached fuse holder bar, spring clamps at the ends of said bar adapted to receive and hold a fuse thereto and when inclosed in said shell to contact respectively with said caps, and a fusible wire gripped by and connecting said clamps.

5. In an electric fuse, an insulated bar adapted to be inserted in a casing, and metallic springs secured to said bar having forked terminations overhanging the respective ends of said bar adapted to receive and hold a fuse wire.

6. In an electric fuse, an insulated bar 70 adapted to be inserted in a casing, metallic springs secured to said bar having forked terminations overhanging the respective ends of said bar, and a socket in each of said spring forks to receive and hold a fuse wire.

7. An electric fuse comprising a shell, caps adapted to close the ends of said shell one of which is removable, an unattached insulation bar capable of insertion into said shell, metallic spring clamps secured to said bar so as to project beyond and overhang the ends of the bar respectively, gripping means in said clamps arranged to receive and hold a fuse wire irrespective of the position of said bar, and means whereby said spring clamps may be further tightened upon the fuse wire and held in compression between said caps after insertion of said bar in said shell.

In testimony whereof I affix my signature 80 in the presence of two subscribing witnesses, at Cleveland, Ohio, this 6th day of February, 1913.

GEORGE FISHER.
